ABSTRACT

A method for deploying a tubular string into a wellbore includes: injecting fluid through a top drive and flow sub into a top of the tubular string and lowering the tubular string into the wellbore. The flow sub: connects the tubular string top to a quill of the top drive, is in a top injection mode, and has a closed port and an open bore. The method further includes halting injection of the fluid through the top drive and lowering of the tubular string. The method further includes, while injection and lowering are halted: disconnecting the flow sub from the tubular string top; adding one or more tubular joints to the tubular string and connecting the flow sub to a top of the added joints. The method further includes resuming injection of the fluid through the top drive and lowering of the tubular string.

CONTINGENT CONTINUOUS CIRCULATION
DRILLING SYSTEM

BACKGROUND OF THE INVENTION

1. Field of the Invention

The present invention generally relates to a contingent continuous circulation drilling system.

2. Description of the Related Art

In many drilling operations to recover hydrocarbons, a drill string made by assembling joints of drill pipe with threaded connections and having a drill bit at the bottom is rotated to move the drill bit. Typically drilling fluid, such as oil or water based mud, is circulated to and through the drill bit to lubricate and cool the bit and to facilitate the removal of cuttings from the wellbore that is being formed. The drilling fluid and cuttings returns to the surface via an annulus formed between the drill string and the wellbore. At the surface, the cuttings are removed from the drilling fluid and the drilling fluid is recycled.

As the drill bit penetrates into the earth and the wellbore is lengthened, more joints of drill pipe are added to the drill string. This involves stopping the drilling while the joints are added. The process is reversed when the drill string is removed or tripped, e.g., to replace the drill bit or to perform other wellbore operations. Interruption of drilling may mean that the circulation of the mud stops and has to be re-started when drilling resumes. This stoppage can cause deleterious effects on the walls of the wellbore being drilled and can lead to formation damage and problems in maintaining an open wellbore. Further, restarting fluid circulation following a cessation of circulation may result in the overpressuring of a formation in which the wellbore is being formed.

SUMMARY OF THE INVENTION

The present invention generally relates to a contingent continuous circulation drilling system. In one embodiment, a method for deploying a tubular string into a wellbore includes: injecting fluid through a top drive and flow sub into a top of the tubular string and lowering the tubular string into the wellbore. The flow sub connects the tubular string top to a quill of the top drive. The flow sub is in a top injection mode. The flow sub has a closed port formed through a wall thereof and an open bore conducting the fluid from the quill into the tubular string top. The method further includes halting injection of the fluid through the top drive and lowering of the tubular string. The method further includes, while injection and lowering are halted: disconnecting the flow sub from the tubular string top; adding one or more tubular joints to the tubular string and connecting the flow sub to a top of the added joints. The method further includes resuming injection of the fluid through the top drive and lowering of the tubular string.

In another embodiment, a top drive system includes a flow sub and a top drive. The flow sub includes a tubular housing having: a longitudinal bore formed therethrough, a flow port formed through a wall thereof, an upper coupling, and a lower coupling for connection to a tubular; a bore valve operable between an open position and a closed position, wherein the bore valve allows free passage through the bore in the open position and isolates an upper portion of the bore from a lower portion of the bore in the closed position; and a valve member for selectively opening and closing the flow port. The top drive includes: a motor operable to rotate a quill; a swivel having an inlet for receiving a Kelly hose and an outlet in fluid communication with the quill; and a backup wrench movable

2

between an upper position and a lower position. The upper coupling is connected to the quill. The backup wrench is engagable with an upper portion of the housing in the upper position. The backup wrench is engageable with a threaded coupling of the tubular in the lower position.

In another embodiment, a method for deploying a tubular string into a wellbore includes injecting fluid through a top drive and flow sub into a top of the tubular string and lowering the tubular string into the wellbore. The flow sub connects the tubular string top to a quill of the top drive. The flow sub is in a top injection mode. The flow sub has a closed port formed through a wall thereof and an open bore conducting the fluid from the quill into the tubular string top. The method further includes halting lowering of the tubular string due to failure of the top drive. The method further includes, while lowering is halted, shifting the flow sub to a side injection mode and injecting the fluid into the port. The method further includes, while injecting the fluid into the port: disconnecting the quill from the flow sub; and servicing or replacing the top drive.

In another embodiment, a method for deploying a tubular string into a wellbore includes injecting fluid through a top drive and flow sub into a top of the tubular string and lowering the tubular string into the wellbore. The flow sub connects the tubular string top to a quill of the top drive. The flow sub is in a top injection mode. The flow sub has a closed port formed through a wall thereof and an open bore conducting the fluid from the quill into the tubular string top. The method further includes halting lowering of the tubular string. The method further includes while lowering is halted, shifting the flow sub to a side injection mode and injecting the fluid into an annulus of the wellbore, thereby circulating from the annulus, up a bore of the tubular string, and to the open port.

In another embodiment, a method for deploying a tubular string into a wellbore includes injecting fluid into an annulus of the wellbore, thereby circulating from the annulus, up a bore of the tubular string, and to an open port of a flow sub connected to a top of the tubular string and lowering the tubular string into the wellbore. The method further includes halting lowering of the tubular string. The method further includes, while lowering is halted: disconnecting the flow sub from the tubular string top; adding one or more tubular joints to the tubular string and connecting the flow sub to a top of the added joints. The method further includes resuming lowering of the tubular string.

BRIEF DESCRIPTION OF THE DRAWINGS

So that the manner in which the above recited features of the present invention can be understood in detail, a more particular description of the invention, briefly summarized above, may be had by reference to embodiments, some of which are illustrated in the appended drawings. It is to be noted, however, that the appended drawings illustrate only typical embodiments of this invention and are therefore not to be considered limiting of its scope, for the invention may admit to other equally effective embodiments.

FIGS. 1A-1C illustrate a drilling system in a drilling mode, according to one embodiment of the present invention.

FIG. 2A illustrates a flow sub of the drilling system in a top injection mode. FIG. 2B illustrates the flow sub shifted to a side injection mode by a clamp of the drilling system.

FIGS. 3A and 3B illustrate the clamp of the drilling system.

FIGS. 4A-4H illustrate extending the drill string in drilling mode.

FIGS. 5A and 5B illustrate extending the drill string in bypass mode.

FIG. 6A illustrates an alternative drilling system in the drilling mode, according to another embodiment of the present invention. FIG. 6B illustrates the alternative drilling system in the bypass mode.

FIG. 7 illustrates optional accessories for a top drive system of any of the drilling systems.

FIGS. 8A-8C illustrate an alternative drilling system in a reverse bypass mode, according to another embodiment of the present invention.

FIGS. 9A-9C illustrate an alternative drilling system in a reverse drilling mode, according to another embodiment of the present invention.

DETAILED DESCRIPTION

FIGS. 1A-1C illustrate a drilling system 1 in a drilling mode, according to one embodiment of the present invention. The drilling system 1 may include a mobile offshore drilling unit (MODU) 1m, such as a semi-submersible, a drilling rig 1r, a fluid handling system 1h, a fluid transport system 1t, and a pressure control assembly (PCA) 1p. The MODU 1m may carry the drilling rig 1r and the fluid handling system 1h aboard and may include a moon pool, through which drilling operations are conducted. The semi-submersible MODU 1m may include a lower barge hull which floats below a surface (aka waterline) 2s of sea 2 and is, therefore, less subject to surface wave action. Stability columns (only one shown) may be mounted on the lower barge hull for supporting an upper hull above the waterline. The upper hull may have one or more decks for carrying the drilling rig 1r and fluid handling system 1h. The MODU 1m may further have a dynamic positioning system (DPS) (not shown) or be moored for maintaining the moon pool in position over a subsea wellhead 50.

Alternatively, the MODU 1m may be a drill ship. Alternatively, a fixed offshore drilling unit or a non-mobile floating offshore drilling unit may be used instead of the MODU 1m. Alternatively, the wellbore may be subsea having a wellhead located adjacent to the waterline and the drilling rig may be a located on a platform adjacent the wellhead. Alternatively, the drilling system may be used for drilling a subterranean (aka land based) wellbore and the MODU 1m may be omitted.

The drilling rig 1r may include a derrick 3 having a rig floor 4 at its lower end having an opening corresponding to the moonpool. The drilling rig 1r may further include a rail 18 (FIG. 4A) extending from the rig floor 4 toward the crown block 8. The drilling rig 1r may further include a top drive 5. The top drive 5 may include an extender 5x (FIG. 4D), motor 5m (FIG. 5B), an inlet 5i, a gear box 5g, a swivel 5r, a quill 5q, a trolley 5t (FIG. 4A), a pipe hoist, and a backup wrench 5w. The top drive motor 5m may be electric or hydraulic and have a rotor and stator. The motor 5m may be operable to rotate the rotor relative to the stator which may also torsionally drive 16 the quill 5q via one or more gears (not shown) of the gear box 5g. The quill 5q may have a coupling (not shown), such as splines, formed at an upper end thereof and torsionally connecting the quill to a mating coupling of one of the gears. Housings of the motor 5m, swivel 5r, gear box 5g, and backup wrench 5w may be connected to one another, such as by fastening, so as to form a non-rotating frame 5f. The top drive 5 may further include an interface (not shown) for receiving power and/or control lines.

The extender 5x may torsionally connect the frame 5f to the trolley 5t and include one or more arms and an actuator, such as a piston and cylinder assembly. The extender arms may pivotally connect to the frame 5f and trolley 5t such that operation of the extender actuator may horizontally extend or retract the frame (and rotating components) relative to the

trolley and rail 18. The trolley 5t may ride along the rail 18, thereby torsionally restraining the frame 5f while allowing vertical movement of the top drive 5 with a travelling block 6. The traveling block 6 may be connected to the frame 5f, such as by fastening to suspend the top drive from the derrick 3. Alternatively, the top drive 5 may include a becket for receiving a hook of the traveling block 6.

The swivel 5r may include one or more bearings for longitudinally and rotationally supporting rotation of the quill 5q relative to the frame 5f. The inlet 5i may have a coupling for connection to a Kelly hose 37h and provide fluid communication between the Kelly hose and a bore of the quill 5q. The quill 5q may have a coupling, such as a threaded pin, formed at a lower end thereof for connection to a mating coupling of a flow sub 100. The pipe hoist may include an elevator 5e, one or more links 5b pivotally connecting the elevator to the top drive frame 5f, and a link tilt (not shown), such as a piston and cylinder assembly, for horizontally extending or retracting the elevator relative to the frame. The elevator 5e may be manually opened and closed or the pipe hoist may include an actuator (not shown) for opening and closing the elevator. Additionally, the top drive 5 may further include a (first) thread compensator (not shown).

The backup wrench 5w may include a tong, a telescoping arm, an arm actuator (not shown), and a tong actuator (not shown). The telescoping arm may torsionally connect the tong to the frame 5f while allowing the arm actuator to longitudinally move the tong relative to the frame. The tong may include a pair of jaws and the tong actuator may radially move one of the jaws radially toward or away from the other jaw. The arm actuator may also operate as a second thread compensator while making up a threaded connection between the flow sub 100 and one or more of the stands 11a,b.

The traveling block 6 may be supported by wire rope 7 connected at its upper end to a crown block 8. The wire rope 7 may be woven through sheaves of the blocks 6, 8 and extend to drawworks 9 for reeling thereof, thereby raising or lowering the traveling block 6 relative to the derrick 3. A top of the drill string 10 may be connected to the flow sub 100, such as by a threaded connection, or by a gripper (not shown), such as a torque head or spear. The drilling rig 1r may further include a drill string compensator (not shown) to account for heave of the MODU 1m. The drill string compensator may be disposed between the traveling block 6 and the top drive 5 (aka hook mounted) or between the crown block 8 and the derrick 3 (aka top mounted).

The fluid transport system it may include the drill string 10, an upper marine riser package (UMRP) 20, a marine riser 25, a booster line 27, and a choke line 28. The drill string 10 may include a bottomhole assembly (BHA) 10b and joints of drill pipe 10p connected together, such as by threaded couplings. The BHA 10b may be connected to the drill pipe 10p, such as by a threaded connection, and include a drill bit 15 and one or more drill collars 12 connected thereto, such as by a threaded connection. The drill bit 15 may be rotated 16 by the top drive 5 via the drill pipe 10p and/or the BHA 10b may further include a drilling motor (not shown, see 612) for rotating the drill bit. The BHA 10b may further include an instrumentation sub (not shown), such as a measurement while drilling (MWD) and/or a logging while drilling (LWD) sub.

The PCA 1p may be connected to a wellhead 50 located adjacent to a floor 2f of the sea 2. A conductor string 51 may be driven into the seafloor 2f. The conductor string 51 may include a housing and joints of conductor pipe connected together, such as by threaded connections. Once the conductor string 51 has been set, a subsea wellbore 90 may be drilled into the seafloor 2f and a casing string 52 may be deployed

into the wellbore. The casing string 52 may include a well-head housing and joints of casing connected together, such as by threaded connections. The wellhead housing may land in the conductor housing during deployment of the casing string 52. The casing string 52 may be cemented 91 into the wellbore 90. The casing string 52 may extend to a depth adjacent a bottom of an upper formation 94u. The upper formation 94u may be non-productive and a lower formation 94b may be a hydrocarbon-bearing reservoir. Alternatively, the lower formation 94b may be environmentally sensitive, such as an aquifer, or unstable. Although shown as vertical, the wellbore 90 may include a vertical portion and a deviated, such as horizontal, portion.

The PCA 1p may include a wellhead adapter 40b, one or more flow crosses 41u,m,b, one or more blow out preventers (BOPs), a lower marine riser package (LMRP), one or more accumulators 44, and a receiver 46. The LMRP may include a control pod 76, a flex joint 43, and a connector 40u. The wellhead adapter 40b, flow crosses 41u,m,b, BOPs, receiver 46, connector 40u, and flex joint 43, may each include a housing having a longitudinal bore therethrough and may each be connected, such as by flanges, such that a continuous bore is maintained therethrough. The bore may have drift diameter, corresponding to a drift diameter of the wellhead 50.

Each of the connector 40u and wellhead adapter 40b may include one or more fasteners, such as dogs, for fastening the LMRP to the BOPs and the PCA 1p to an external profile of the wellhead housing, respectively. Each of the connector 40u and wellhead adapter 40b may further include a seal sleeve for engaging an internal profile of the respective receiver 46 and wellhead housing. Each of the connector 40u and wellhead adapter 40b may be in electric or hydraulic communication with the control pod 76 and/or further include an electric or hydraulic actuator and an interface, such as a hot stab, so that a remotely operated subsea vehicle (ROV) (not shown) may operate the actuator for engaging the dogs with the external profile.

The LMRP may receive a lower end of the riser 25 and connect the riser to the PCA 1p. The control pod 76 may be in electric, hydraulic, and/or optical communication with a programmable logic controller (PLC) 75 onboard the MODU 1m via an umbilical 70. The control pod 76 may include one or more control valves (not shown) in communication with the BOPs for operation thereof. Each control valve may include an electric or hydraulic actuator in communication with the umbilical 70. The umbilical 70 may include one or more hydraulic or electric control conduit/cables for the actuators. The accumulators 44 may store pressurized hydraulic fluid for operating the BOPs. Additionally, the accumulators 44 may be used for operating one or more of the other components of the PCA 1p. The umbilical 70 may further include hydraulic, electric, and/or optic control conduit/cables for operating various functions of the PCA 1p. The PLC 75 may operate the PCA 1p via the umbilical 70 and the control pod 76.

A lower end of the booster line 27 may be connected to a branch of the flow cross 41u by a shutoff valve 45a. A booster manifold may also connect to the booster line lower end and have a prong connected to a respective branch of each flow cross 41m,b. Shutoff valves 45b,c may be disposed in respective prongs of the booster manifold. Alternatively, a separate kill line (not shown) may be connected to the branches of the flow crosses 41m,b instead of the booster manifold. An upper end of the booster line 27 may be connected to an outlet of a booster pump (not shown). A lower end of the choke line 28 may have prongs connected to respective second branches of

the flow crosses 41m,b. Shutoff valves 45d,e may be disposed in respective prongs of the choke line lower end.

A pressure sensor 47a may be connected to a second branch of the upper flow cross 41u. Pressure sensors 47b,c 5 may be connected to the choke line prongs between respective shutoff valves 45d,e and respective flow cross second branches. Each pressure sensor 47a-c may be in data communication with the control pod 76. The lines 27, 28 and umbilical 70 may extend between the MODU 1m and the PCA 1p by being fastened to brackets disposed along the riser 25. Each line 27, 28 may be a flow conduit, such as coiled tubing. Each shutoff valve 45a-e may be automated and have a hydraulic actuator (not shown) operable by the control pod 76 via fluid communication with a respective umbilical conduit or the LMRP accumulators 44. Alternatively, the valve actuators may be electrical or pneumatic.

The riser 25 may extend from the PCA 1p to the MODU 1m and may connect to the MODU via the UMRP 20. The UMRP 20 may include a diverter 21, a flex joint 22, a slip (aka telescopic) joint 23, a tensioner 24, and a rotating control device (RCD) 26. A lower end of the RCD 26 may be connected to an upper end of the riser 25, such as by a flanged connection. The slip joint 23 may include an outer barrel connected to an upper end of the RCD 26, such as by a flanged connection, and an inner barrel connected to the flex joint 22, such as by a flanged connection. The outer barrel may also be connected to the tensioner 24, such as by a tensioner ring (not shown).

The flex joint 22 may also connect to the diverter 21, such 30 as by a flanged connection. The diverter 21 may also be connected to the rig floor 4, such as by a bracket. The slip joint 23 may be operable to extend and retract in response to heave of the MODU 1m relative to the riser 25 while the tensioner 24 may reel wire rope in response to the heave, thereby supporting the riser 25 from the MODU 1m while accommodating the heave. The flex joints 23, 43 may accommodate respective horizontal and/or rotational (aka pitch and roll) movement of the MODU 1m relative to the riser 25 and the riser relative to the PCA 1p. The riser 25 may have one or more buoyancy 35 modules (not shown) disposed therealong to reduce load on the tensioner 24.

The RCD 26 may include a housing, a piston, a latch, and a rider. The housing may be tubular and have one or more sections connected together, such as by flanged connections. 45 The rider may include a bearing assembly, a housing seal assembly, one or more strippers, and a catch sleeve. The rider may be selectively longitudinally and torsionally connected to the housing by engagement of the latch with the catch sleeve. The housing may have hydraulic ports in fluid communication with the piston and an interface of the RCD 26. The bearing assembly may support the strippers from the sleeve such that the strippers may rotate relative to the housing (and the sleeve). The bearing assembly may include one or more radial bearings, one or more thrust bearings, and a 50 self contained lubricant system. The bearing assembly may be disposed between the strippers and be housed in and connected to the catch sleeve, such as by a threaded connection and/or fasteners.

Each stripper may include a gland or retainer and a seal. 60 Each stripper seal may be directional and oriented to seal against the drill pipe 10p in response to higher pressure in the riser 25 than the UMRP 20. Each stripper seal may have a conical shape for fluid pressure to act against a respective tapered surface thereof, thereby generating sealing pressure against the drill pipe 10p. Each stripper seal may have an inner diameter slightly less than a pipe diameter of the drill pipe 10p to form an interference fit therebetween. Each strip-

per seal may be flexible enough to accommodate and seal against threaded couplings of the drill pipe **10p** having a larger tool joint diameter. The drill pipe **10p** may be received through a bore of the rider so that the stripper seals may engage the drill pipe. The stripper seals may provide a desired barrier in the riser **25** either when the drill pipe **10p** is stationary or rotating. The RCD **26** may be submerged adjacent the waterline **2s**. The RCD interface may be in fluid communication with an auxiliary hydraulic power unit (HPU) (not shown) of the PLC **75** via an auxiliary umbilical **71**.

Alternatively, an active seal RCD may be used. Alternatively, the RCD **26** may be located above the waterline **2s** and/or along the UMRP **20** at any other location besides a lower end thereof. Alternatively, the RCD **26** may be assembled as part of the riser **25** at any location therealong or as part of the PCA **1p**.

The fluid handling system **1h** may include a return line **29**, mud pump **30d**, one or more hydraulic power units (HPUs) **30h** (one shown in FIG. 1A and two shown in FIG. 5B), a bypass line **31p,h**, one or more hydraulic lines **31c**, a drain line **32**, a solids separator, such as a shale shaker **33**, one or more flow meters **34b,d,r**, one or more pressure sensors **35b,d,r**, one or more variable choke valves, such as chokes **36p,r**, a supply line, one or more shutoff valves **38a-d**, a hydraulic manifold **39**, and a clamp **200**.

A lower end of the return line **29** may be connected to an outlet of the RCD **26** and an upper end of the return line may be connected to an inlet of the shaker **33**. The returns pressure sensor **35r**, returns choke **36r**, and returns flow meter **34r** may be assembled as part of the return line **29**. A transfer line **61** may connect an outlet of the shaker **33** to an inlet of the mud pump **30d**. A lower end of the supply line may be connected to an outlet of the mud pump **30d** and an upper end of the supply line may be connected to the top drive inlet **5i**. The supply pressure sensor **35d**, supply flow meter **34d**, and supply shutoff valve **38a** may be assembled as part of the supply line. A first end of the bypass line **31p,h** may be connected to an outlet of the mud pump **30d** and a second end of the bypass line may be connected to an inlet **207** (FIG. 3A) of the clamp **200**. The bypass pressure sensor **35b**, bypass flow meter **34b**, and bypass shutoff valve **38b** may be assembled as part of the bypass line **31p,h**.

A first end of the drain line **32** may be connected to the transfer line **61** and a second portion of the drain line may have prongs (four shown). A first drain prong may be connected to the bypass line **31p,h**. A second drain prong may be connected to the supply line. Third and fourth drain prongs may be connected to an outlet of the mud pump **30d**. The supply drain valve **38c**, bypass drain valve **38d**, pressure choke **36p**, and flow choke **36f** may be assembled as part of the drain line **32**. A first end of the hydraulic lines **31c** may be connected to the HPU **30h** and a second end of the hydraulic lines may be connected to the clamp **200**. The hydraulic manifold **39** may be assembled as part of the hydraulic lines **31c**.

Each choke **36p,r** may include a hydraulic actuator operated by the PLC **75** via the auxiliary HPU (not shown). The returns choke **36r** may be operated by the PLC **75** to maintain backpressure in the riser **25**. The flow choke **36f** may be operated by the PLC **75** to prevent a flow rate supplied to the flow sub **100** and clamp **200** in bypass mode from exceeding a maximum allowable flow rate of the flow sub and/or clamp. Alternatively, the choke actuators may be electrical or pneumatic. The pressure choke **36p** may be operated by the PLC **75** to protect against overpressure of the clamp **200** by the mud pump **30d**. Each shutoff valve **38a-d** may be automated and have a hydraulic actuator (not shown) operable by the

PLC **75** via the auxiliary HPU. Alternatively, the valve actuators may be electrical or pneumatic.

Each pressure sensor **35b,d,r** may be in data communication with the PLC **75**. The returns pressure sensor **35r** may be operable to measure backpressure exerted by the returns choke **36**. The supply pressure sensor **35d** may be operable to measure standpipe pressure. The bypass pressure sensor **35b** may be operable to measure pressure of the clamp inlet **207**. The returns flow meter **34r** may be a mass flow meter, such as a Coriolis flow meter, and may be in data communication with the PLC **75**. The returns flow meter **34r** may be connected in the return line **29** downstream of the returns choke **36r** and may be operable to measure a flow rate of the returns **60r**. Each of the supply **34d** and bypass **34b** flow meters may be a volumetric flow meter, such as a Venturi flow meter. The supply flow meter **34d** may be operable to measure a flow rate of drilling fluid supplied by the mud pump **30d** to the drill string **10** via the top drive **5**. The bypass flow meter **34b** may be operable to measure a flow rate of drilling fluid supplied by the mud pump **30d** to the clamp inlet **207**. The PLC **75** may receive a density measurement of the drilling fluid **60d** from a mud blender (not shown) to determine a mass flow rate of the drilling fluid. Alternatively, the bypass **34b** and supply **34d** flow meters may each be mass flow meters.

In the drilling mode, the mud pump **30d** may pump drilling fluid **60d** from the transfer line **61** (or fluid tank connected thereto), through the pump outlet, standpipe **37p** and Kelly hose **37h** to the top drive **5**. The drilling fluid **60d** may include a base liquid. The base liquid may be base oil, water, brine, or a water/oil emulsion. The base oil may be diesel, kerosene, naphtha, mineral oil, or synthetic oil. The drilling fluid **60d** may further include solids dissolved or suspended in the base liquid, such as organophilic clay, lignite, and/or asphalt, thereby forming a mud.

The drilling fluid **60d** may flow from the Kelly hose **37h** and into the drill string **10** via the top drive **5** and flow sub **100**. The drilling fluid **60d** may flow down through the drill string **10** and exit the drill bit **15**, where the fluid may circulate the cuttings away from the bit and return the cuttings up an annulus **95** formed between an inner surface of the casing **91** or wellbore **90** and an outer surface of the drill string **10**. The returns **60r** (drilling fluid **60d** plus cuttings) may flow through the annulus **95** to the wellhead **50**. The returns **60r** may continue from the wellhead **50** and into the riser **25** via the PCA **1p**. The returns **60r** may flow up the riser **25** to the RCD **26**. The returns **60r** may be diverted by the RCD **26** into the return line **29** via the RCD outlet. The returns **60r** may continue through the returns choke **36r** and the flow meter **34r**. The returns **60r** may then flow into the shale shaker **33** and be processed thereby to remove the cuttings, thereby completing a cycle. As the drilling fluid **60d** and returns **60r** circulate, the drill string **10** may be rotated **16** by the top drive **5** and lowered by the traveling block **6**, thereby extending the wellbore **90** into the lower formation **94b**.

The PLC **75** may be programmed to operate the returns choke **36r** so that a target bottomhole pressure (BHP) is maintained in the annulus **95** during the drilling operation. The target BHP may be selected to be within a drilling window defined as greater than or equal to a minimum threshold pressure, such as pore pressure, of the lower formation **94b** and less than or equal to a maximum threshold pressure, such as fracture pressure, of the lower formation, such as an average of the pore and fracture BHPs. Alternatively, the minimum threshold may be stability pressure and/or the maximum threshold may be leakoff pressure. Alternatively, threshold pressure gradients may be used instead of pressures and the gradients may be at other depths along the lower

formation 94b besides bottomhole, such as the depth of the maximum pore gradient and the depth of the minimum fracture gradient. Alternatively, the PLC 75 may be free to vary the BHP within the window during the drilling operation.

A static density of the drilling fluid 60d (typically assumed equal to returns 60r; effect of cuttings typically assumed to be negligible) may correspond to a threshold pressure gradient of the lower formation 94b, such as being greater than or equal to a pore pressure gradient. During the drilling operation, the PLC 75 may execute a real time simulation of the drilling operation in order to predict the actual BHP from measured data, such as standpipe pressure from sensor 35d, mud pump flow rate from the supply flow meter 34d, well-head pressure from an of the sensors 47a-c, and return fluid flow rate from the return flow meter 34r. The PLC 75 may then compare the predicted BHP to the target BHP and adjust the returns choke 36r accordingly.

During the drilling operation, the PLC 75 may also perform a mass balance to monitor for instability of the lower formation 94b, such as a kick (not shown) or lost circulation (not shown). As the drilling fluid 60d is being pumped into the wellbore 90 by the mud pump 30d and the returns 60r are being received from the return line 29, the PLC 75 may compare the mass flow rates (i.e., drilling fluid flow rate minus returns flow rate) using the respective flow meters 34d,r. The PLC 75 may use the mass balance to monitor for formation fluid (not shown) entering the annulus 95 and contaminating the returns 60r or returns 60r entering the formation 94b.

Upon detection of instability, the PLC 75 may take remedial action, such as diverting the flow of returns 60r from an outlet of the returns flow meter to a degassing spool (not shown). The degassing spool may include automated shutoff valves at each end, a mud-gas separator (MGS), and a gas detector. A first end of the degassing spool may be connected to the returns line 29 between the returns flow meter 34r and the shaker 33 and a second end of the degasser spool may be connected to an inlet of the shaker. The gas detector may include a probe having a membrane for sampling gas from the returns 60r, a gas chromatograph, and a carrier system for delivering the gas sample to the chromatograph. The MGS may include an inlet and a liquid outlet assembled as part of the degassing spool and a gas outlet connected to a flare or a gas storage vessel. The PLC 75 may also adjust the returns choke 36r accordingly, such as tightening the choke in response to a kick and loosening the choke in response to loss of the returns.

Alternatively, the PLC 75 may include other factors in the mass balance, such as displacement of the drill string and/or cuttings removal. The PLC 75 may calculate a rate of penetration (ROP) of the drill bit 15 by being in communication with the drawworks 9 and/or from a pipe tally. A mass flow meter may be added to the cuttings chute of the shaker 33 and the PLC 75 may directly measure the cuttings mass rate.

Additionally, the PLC may monitor for other instability issues, such as differential sticking and/or collapse of the wellbore 90 by being in data communication with the top drive 5 for receiving torque exerted by the top drive and/or angular speed of the quill 5q.

FIG. 2A illustrates the flow sub 100 in a top injection mode. FIG. 2B illustrates the flow sub 100 shifted to a side injection mode by the clamp 200. The flow sub 100 may include a tubular housing 105, a bore valve 110, a bore valve actuator, and a side port valve 120. The housing 105 may include one or more sections, such as an upper section 105u and a lower 105b section, each section connected together, such as by a threaded connection. An outer diameter of the housing 105

may correspond to the tool joint diameter of the drill pipe 10p to maintain compatibility with the RCD 26. The housing 105 may have a central longitudinal bore formed therethrough and a radial flow port 101 formed through a wall thereof in fluid communication with the bore (in this mode) and located at a side of the lower housing section 105b. The housing 105 may also have a threaded coupling at each longitudinal end, such as box 106b formed in an upper longitudinal end and a pin 106p formed on a lower longitudinal end, so that the housing 105 may connect a top of the drill string 10 to the quill 5q. Except for seals and where otherwise specified, the flow sub 100 may be made from a metal or alloy, such as steel, stainless steel, or a nickel based alloy. Seals may be made from a polymer, such as a thermoplastic, elastomer, or copolymer and may or may not be housed in a gland.

The bore valve 110 may include a closure member, such as a ball 111, a seat 112, and a body, such as a cage 113. The cage 113 may include one or more sections, such as an upper section 113u and a lower 113b section. The lower cage section 113b may be disposed within the housing 105 and connected thereto, such as by a threaded connection and engagement with a lower shoulder 103b of the housing 105. The upper cage section 113u may be disposed within the housing 105 and connected thereto, such as by entrapment between the ball 111 and an upper shoulder 103u of the housing. The upper shoulder 103u may be formed in an inner surface of the upper housing section 105u and the lower shoulder 103b may be a top of the lower housing section 105b. The seat 112 may include a seal 112s and a retainer 112r. The seat retainer 112r may be connected to the upper cage section 113u, such as by a threaded connection. The seat seal 112s may be connected to the upper cage section 113u, such as by a lip and groove connection and by being disposed between the upper cage section and the seat retainer 112r. A top of the lower cage section 113b may serve as a stopper 113s for the ball 111.

The ball 111 may be disposed between the cage sections 113u,b and may be rotatable relative thereto. The ball 111 may be operable between an open position (FIG. 2A) and a closed position (FIGS. 2B and 5B) by the bore valve actuator. The ball 111 may have a bore formed therethrough corresponding to the housing bore and aligned therewith in the open position. A wall of the ball 111 may close an upper portion of the housing bore in the closed position and the ball 111 may engage the seat seal 112s in response to pressure exerted against the ball by fluid injection into the side port 101.

The port valve 120 may include a closure member, such as a sleeve 121, and a seal mandrel 122. The seal mandrel 122 may be made from an erosion resistant material, such as tool steel, ceramic, or cermet. The seal mandrel 122 may be disposed within the housing 105 and connected thereto, such as by one or more (two shown) fasteners 123. The seal mandrel 122 may have a port formed through a wall thereof corresponding to and aligned with the side port 101. Lower seals 124b may be disposed between the housing 105 and the seal mandrel 122 and between the seal mandrel and the sleeve 121 to isolate the interfaces thereof. The port valve 120 may have a maximum allowable flow rate greater than, equal to, or slightly less than a flow rate of the drilling fluid 60d in drilling mode.

The sleeve 121 may be disposed within the housing 105 and longitudinally moveable relative thereto between an open position (FIGS. 2B and 5B) and a closed position (FIG. 2A) by the clamp 200. In the open position, the side port 101 may be in fluid communication with a lower portion of the housing bore. In the closed position, the sleeve 121 may isolate the side port 101 from the housing bore by engagement with the

11

lower seals 124b of the seal sleeve 122. The sleeve may include an upper portion 121u, a lower portion 121b, and a lug 121c disposed between the upper and lower portions.

A window 102 may be formed through a wall of the lower housing section 105b and may extend a length corresponding to a stroke of the port valve 120. The window 102 may be aligned with the side port 101. The lug 121c may be accessible through the window 102. A recess 104 may be formed in an outer surface of the lower housing section 105b adjacent to the side port 101 for receiving a stab connector 209 formed at the clamp inlet 207. Mid seals 124m may be disposed between the housing 105 and the lower cage section 113b and between the lower cage section and the sleeve 121 to isolate the interfaces thereof.

The bore valve actuator may be mechanical and include a cam 115, a linkage, such as one or more (two shown) pins 116 and slots 121s, and a toggle, such as a split ring 117. An upper annulus may be formed between the cage 113 and the upper housing section 105u and a lower annulus may be formed between the valve sleeve 121 and the lower housing section 105b. The cam 115 may be disposed in the upper annulus and may be longitudinally movable relative to the housing 105. The cam 115 may interact with the ball 111, such as by having one or more (two shown) followers 115f, each formed in an inner surface of a body 115b thereof and extending into a respective cam profile (not shown) formed in an outer surface of the ball 111 or vice versa. Alternatively, each follower 115f may be a separate member fastened to the cam body 115b. The ball-cam interaction may rotate the ball 111 between the open and closed positions in response to longitudinal movement of the cam 115 relative to the ball.

The cam 115 may also interact with the valve sleeve 121 via the linkage. The pins 116 may each be fastened to the cam body 115b and each extend into the respective slot 121s formed through a wall of the sleeve upper portion 121u or vice versa. The split ring 117 may be fastened to the sleeve 121 by being received in a groove formed in an inner surface of the sleeve upper portion 121u at a lower portion of the slots 121s. The lower cage section 113b may have an opening 113o formed therethrough for accommodating the cam-sleeve interaction. The linkage may longitudinally connect the cam 115 and the sleeve 121 after allowing a predetermined amount of longitudinal movement therebetween. A stroke of the cam 115 may be less than a stroke of the sleeve 121, such that when coupled with the lag created by the linkage, the bore valve 110 and the port valve 120 may never both be fully closed simultaneously. Upper seals 124u may be disposed between the housing 105 and the cam 115 and between the upper cage section 113u and the cam to isolate the interfaces thereof.

FIGS. 3A and 3B illustrate the clamp 200. The clamp 200 may include a body 201, a band 202, a latch 205 operable to fasten the band to the body, an inlet 207, one or more actuators, such as port valve actuator 210 and a band actuator 220, and a hub 239. The clamp 200 may be movable between an open position (not shown) for receiving the flow sub 100 and a closed position for surrounding an outer surface of the lower housing segment 105b. The body 201 may have a lower base portion 201b and an upper stem portion 201s. The body 201 may have a coupling, such as a hinge portion, formed at an end of the base portion 201b, and the band 202 may have a mating coupling, such as a hinge portion, formed at a first end thereof. The hinge portions may be connected by a fastener, such as a pin 204, thereby pivotally connecting the band 202 and the body 201. The band 202 may have a lap formed at a second end thereof for mating with a complementary lap

12

formed at an end of the latch 205. Engagement of the laps may form a lap joint to circumferentially connect the band 202 and the latch 205.

The body 201 may have a port 201p formed through the base portion 201b for receiving the inlet 207. The inlet 207 may be connected to the body 201, such as by a threaded connection. A mud saver valve (MSV) 238 (FIG. 5B) may be connected to the inlet 207, such as by a threaded connection. An adapter (not shown) may be connected to the MSV 238, such as by a threaded connection. The adapter may have a coupling, such as flange, for receiving a flexible conduit, such as bypass hose 31h. The inlet 207 may further have one or more seals 208a,b and the stab connector 209 formed at an end thereof engaging a seal face of the flow sub 100 adjacent to the side port 101.

The port valve actuator 210 may include the stem portion 201s, a bracket 212, a yoke 213, a hydraulic motor 215, and a gear train 216, 217. The body 201 may have a window formed through the stem portion 201s and guide profiles, such as tracks 211, formed in an inner surface of the stem portion adjacent to the window. The yoke 213 may extend through the window and have a nut portion 213n, slider portion 213s, and tongue portion 213t. The slider portion 213s may be engaged with the tracks 211, thereby allowing longitudinal movement 25 of the yoke 213 relative to the body 201. The yoke 213 may have an engagement profile, such as a lip 213p, formed at an end of the tongue portion 213t for engaging a groove formed in an outer surface of the lug 121c, thereby longitudinally connecting the yoke with the flow sub sleeve 121. The hydraulic motor 215 may have a stator connected to the bracket 212, such as by one or more (four shown) fasteners 214, and a rotor connected to a drive gear 216 of the gear train 216, 217. The motor 215 may be bidirectional.

The drive gear 216 may be connected to a yoke gear 217 by 35 meshing of teeth thereof. The yoke gear 217 may be connected to a lead screw 218, such as by interference fit or key/keyway. The nut portion 213n may be engaged with the lead screw 218 such that the yoke 213 may be being raised and lowered by respective rotation of the lead screw. The bracket 212 may be connected to the body 201, such as by one or more (three shown) fasteners 240. The lead screw 218 may be supported by the bracket 212 for rotation relative thereto by one or more bearings 219. The motor 215 may be operable to raise and lower the yoke 213 relative to the body 201, thereby 45 also operating the flow sub sleeve 121 when the clamp 200 is engaged with the flow sub 100. Alternatively, the motor 215 may be electric or pneumatic.

The band actuator 220 may be operable to tightly engage the clamp 200 with the lower housing section 105b after the latch 105 has been fastened. The band actuator 220 may include a bracket 222, a hydraulic motor 225, a bearing 229, and a tensioner. The tensioner may include a tensioner bolt 224a, a stopper 224b, and a tubular tensioner nut 226. The motor 225 may have a stator connected to the bearing 229, such as by one or more fasteners (not shown) and a rotor connected to a tensioner bolt 224a. The motor 225 may be bidirectional. The tensioner bolt 224a may be supported from the body 201 for rotation relative thereto by the bearing 229. The bracket 222 may be connected to the body 201, such as by one or more (five shown) fasteners 241. The bearing 229 may be connected to the bracket 222, such as by a fastener 242.

The latch 205 may include an opening formed therethrough for receiving the tensioner nut 226 and a cavity formed therein for facilitating assembly of the tensioner. To 65 further facilitate assembly, the tensioner nut 226 may be connected to a bar 227, such as by fastener 244b and a pin (slightly visible in FIG. 3B). The bar 227 may have a slot

formed therethrough to accommodate operation of the tensioner. The bar 227 may also be connected to the bracket, such as by fastener 244a. The tensioner nut 226 may rotate relative to the opening and may have a threaded bore for receiving the tensioner bolt 224a. Rotation of the tensioner nut 226 may prevent binding of the tensioner bolt 224a and may allow replacement due to wear. The stopper 224b may be connected to the bolt 224a with a threaded connection. To engage the clamp 200 with the flow sub 100, the body 201 may be aligned with the flow sub 100, the band 202 wrapped around the flow sub 100 and the latch 205 engaged with the band 202. The motor 225 may then be operated, thereby tightening the clamp 200 around the lower housing section 105b. Alternatively, the motor 225 may be electric or pneumatic.

To facilitate manual handling, the clamp 200 may further include one or more handles 230a-d. A first handle 230a may be connected to the band 202, such as by a fastener. Second 230b and third 230c handles may be connected to the latch 205, such as by respective fasteners. A fourth handle 230d may be connected to the bracket 222, such as by a fastener. A hub 239 may be connected to the bracket 212, such as by one or more (two shown) fasteners 243. The hub 239 may include one or more (four shown) hydraulic connectors 245 for receiving respective hydraulic lines 31c from the hydraulic manifold 39. The hub 239 may also include internal hydraulic conduits (not shown), such as tubing, connecting the connectors 245 to respective inlets and outlets of the hydraulic motors 215, 225.

Each hydraulic motor 215, 225 may further include a motor lock operable between a locked position and an unlocked position. Each motor lock may include a clutch torsionally connecting the respective rotor and the stator in the locked position and disengaging the respective rotor from the respective stator in the unlocked position. Each clutch may be biased toward the locked position and further include an actuator, such as a piston, operable to move the clutch to the unlocked position in response to hydraulic fluid being supplied to the respective motor.

FIGS. 4A-4H illustrate adding a stand 11a of drill pipe 10p to the drill string 10 in drilling mode. If no instability has been detected, the drill string 10 may be extended in the drilling mode once a top of the drill string 10 reaches the rig floor 4. Drilling may be stopped by stopping advancement and rotation 16 of the top drive and removing weight from the drill bit 15. A spider 19 may then be operated to engage the drill string 10, thereby longitudinally supporting the drill string 10 from the rig floor 4. A drive tong 65d may be engaged with the flow sub 100 and a backup tong 65b may be engaged with the top of the drill string 10. The first top drive thread compensator may be operated to accommodate longitudinal movement of the threaded connection between the flow sub 100 and the drill string 10.

The drive tong 65d may then be operated to loosen the connection between the flow sub 100 and the drill string 10. Once the connection has been loosened, the drive tong 65d may be disengaged from the flow sub 100 and the top drive motor 5m may be operated to finish unscrewing the connection. The top drive 5 may then be raised until the elevator 5e is proximate to a top of the stand 11a. The elevator 5e may be opened (or already open), engaged with the stand 11a and closed to securely grip the stand. The top drive 5 and stand 11a may then be raised and the link-tilt operated to swing the stand into alignment with the drill string 10. The top drive 5 and stand 11a may be lowered and a bottom coupling of the stand stabbed into the top coupling of the drill string 10.

The top drive first thread compensator may again be operated and a spinner (not shown) may be engaged with the stand

11a and operated to spin the connection between the stand 11a and the drill string 10. The drive tong 65d may be engaged with the bottom coupling and the backup tong 65b may still be engaged with the top coupling of the drill string 10. The drive tong 65d may then be operated to tighten the connection between the stand 11a and the drill string 10. Once the connection has been tightened, the tongs 65d,b may be disengaged. The elevator 5e may be partially opened to release the stand 11a and the top drive 5 lowered relative to the stand. The backup wrench arm actuator may be operated to lower the tong to a position adjacent a top coupling of the stand 11a. The tong actuator may then be operated to engage the backup wrench tong with the top coupling of the stand 11a, the elevator 5e may be fully opened, and the link-tilt operated to clear the elevator. The arm actuator may then be operated as the second thread compensator and the top drive motor 5m operated to spin and tighten the connection between the flow sub 100 and the stand 11a.

The spider 19 may then be operated to release the drill string 10. Once released, the top drive motor 5m may be operated to rotate 16 the drill string 10. Weight may be added to the drill bit 15, thereby advancing the drill string 10 into the wellbore 90 and resuming drilling of the wellbore. The process may be repeated until the wellbore 90 has been drilled to total depth or a depth for setting another string of casing, or instability is detected.

FIGS. 5A and 5B illustrate extending the drill string 10 in bypass mode. If instability has been detected, the drill string 10 may be extended in bypass mode once the top of the drill string 10 reaches the rig floor 4. In preparation of the shift, the stand 11b may be replaced by a modified stand 81. The modified stand 81 may include a second continuous flow sub 100b and one or more joints of drill pipe 10p. Drilling may be stopped by stopping advancement and rotation 16 of the top drive 5 and removing weight from the drill bit 15. The spider 19 may then be operated to engage the drill string 10, thereby longitudinally supporting the drill string 10 from the rig floor 4. The clamp 200 may then be transported to the flow sub 100 and closed around the flow sub lower housing section 105b. The PLC 75 may then operate the band actuator 220 by opening manifold valves 39a,d, thereby supplying hydraulic fluid to the band motor 225. Operation of the band motor 225 may rotate the tensioner bolt 224a, thereby tightening the clamp 200 into engagement with the flow sub lower housing 105b. The PLC 75 may then lock the band motor 225. The MSV 238 may be opened and then the rig crew may evacuate the rig floor 4.

A position sensor 250 may be operably coupled to the MSV 238 for determining a position (open or closed) of the MSV. The position sensor 250 may be in data communication with the PLC 75. The fluid handling system 1h may further include a second HPU 30h and a second manifold 39. Each HPU 30h may include a pump, an accumulator, a check valve, a reservoir having hydraulic fluid, and internal hydraulic conduits connecting the pump, reservoir, accumulator, and check valve. Each HPU 30h may further include a pressurized port in fluid communication with the respective accumulator and a drain port in fluid communication with the reservoir. Each hydraulic manifold 39 may include one or more automated shutoff valves 39a-d, 39e-h in communication with the PLC 75. Each manifold 39 may have a pressurized inlet in connected to a first respective pair of the shutoff valves and a drain inlet in fluid communication with a second respective pair of shutoff valves. Each manifold 39 may also have first and second outlets, each outlet connected to a shutoff valve of each pair. A first portion of the hydraulic lines 31c may connect respective inlets of the manifolds to respective inlets

of the HPUs 30h. A second portion of the hydraulic lines 31c may connect respective outlets of the manifolds to respective hydraulic connectors 245 of the clamp hub 239. Alternatively, each manifold 39 may include one or more directional control valves, each directional control valve consolidating two or more of the shutoff valves 39a-h.

The PLC 75 may then test engagement of the seals 208a,b by closing the bypass drain valve 38d and by opening the bypass valve 38b to pressurize the clamp inlet 207 and then closing the bypass valve. If the clamp seals 208a,b are not securely engaged with the lower housing section 105b, drilling fluid 60d will leak past the clamp seals. The PLC 75 may verify sealing integrity by monitoring the bypass pressure sensor 35b. The PLC 75 may then reopen the bypass valve 38b to equalize pressure on the valve sleeve 121. The PLC 75 may then operate the port valve actuator 210 by opening manifold valves 39f,h, thereby supplying hydraulic fluid to the port motor 215. Operation of the port motor 215 may rotate the lead screw 218, thereby raising the yoke 213.

When moved upwardly by the yoke 213, the sleeve 121 may move longitudinally relative to the cam 115 until the split ring 117 engages the pins 116, thereby longitudinally connecting the sleeve and the cam. Upward movement of the sleeve 121 and the cam 115 may continue, thereby closing the bore valve 110. Drilling fluid 60d may momentarily flow into the drill string 10 through both the side port 101 and the bore valve 110. The upward movement may continue until a top of the cam 115 engages the upper housing shoulder 103u. The split ring 117 may then be pushed radially inward by further engagement with the pins 116, thereby freeing the cam 115 from the sleeve 121. Upward movement of the sleeve 121 (without the cam 115) may continue until an upper shoulder of the yoke 213 engages an upper shoulder of the stem portion 201s at which point the side port 101 is fully open. Once the side port 101 is fully open, the PLC 75 may lock the port motor 215 and relieve pressure from the top drive 5 by closing the supply valve 38a and opening the supply drain valve 38c. The PLC 75 may then test integrity of the closed bore valve 110 by closing the supply drain valve 38d. The PLC 75 may verify closing of the bore valve 110 by monitoring the supply pressure sensor 35d.

The tong actuator may then be operated to engage the backup wrench tong with the flow sub 100 and the top drive motor 5m operated to disconnect the quill 5q from the flow sub 100. The top drive 5 may then be raised until the elevator 5e is proximate to a top of the second flow sub 100b. The elevator 5e may be opened (or already open), engaged with the second flow sub 100b and closed to securely grip the modified stand 81. The top drive 5 and modified stand 81 may then be raised and the link-tilt operated to swing the modified stand into alignment with the drill string 10 and flow sub 100. The rig crew may then return to the rig floor 4. The top drive 5 and modified stand 81 may be lowered and a bottom coupling of the modified stand stabbed into the top coupling 106b of the flow sub 100. The top drive first thread compensator may again be operated and the spinner may be operated to spin the connection between the modified stand 81 and the flow sub 100. The drive tong 65d and backup tong 65b may then be used to tighten the connection. The rig crew may then leave the rig floor 4. The connection between the quill 5q and the second flow sub 100b may then be made in a similar fashion as discussed above for the connection between the flow sub 100 and the stand 11a.

Drilling fluid 60d may continue to be injected into the side port 101 (via the open supply valve 38b and MSV 238) during adding of the modified stand 81 by the top drive 5 at a flow rate corresponding to the flow rate in drilling mode. The PLC 75

may also utilize the bypass flow meter 34b for performing the mass balance to monitor for a kick or lost circulation during adding of the modified stand 81. Once the modified stand 81 has been added to the drill string 10, the PLC 75 may pressurize the added stand 81 by closing the supply drain valve 38c and opening the supply valve 38a. Once the added stand 81 has been pressurized, the PLC 75 may then unlock the port motor 215. The PLC 75 may then reverse operate the port valve actuator 210 by opening manifold valves 39e,g, thereby reversing supply of the hydraulic fluid to the port motor 215. Operation of the port motor 215 may counter-rotate the lead screw 218, thereby lowering the yoke 213.

When moved downwardly by the yoke 213, the sleeve 121 may move longitudinally relative to the cam 115 until the split ring 117 engages the pins 116, thereby longitudinally connecting the sleeve and the cam. Downward movement of the sleeve 121 and the cam 115 may continue, thereby opening the bore valve 110. Drilling fluid 60d may momentarily flow into the drill string 10 through both the side port 101 and the bore valve 110. The downward movement may continue until a bottom of the cam 115 engages a shoulder of the lower cage section 113b. The split ring 117 may then be pushed radially inward by further engagement with the pins 116, thereby freeing the cam 115 from the sleeve 121. Downward movement of the sleeve 121 (without the cam 115) may continue until a lower shoulder of the yoke 213 engages a lower shoulder of the stem portion 201s at which point the side port 101 is fully closed.

Once the side port 101 is fully closed, the PLC 75 may then relieve pressure from the clamp inlet 207 by closing the bypass valve 38b and opening the bypass drain valve 38d. The PLC 75 may then confirm closure of the port sleeve 121 by closing the bypass drain valve 38d and monitoring the bypass pressure sensor 35b. Once closure of the port sleeve 121 has been confirmed, the PLC 75 may open the bypass drain valve 38d. The rig crew may then return to the rig floor 4 and close the MSV 238. The PLC 75 may then unlock the band motor 225. The PLC 75 may then reverse operate the band actuator 220 by opening manifold valves 39b,c, thereby reversing supply of hydraulic fluid to the band motor 225. Operation of the band motor 225 may counter-rotate the tensioner bolt 224a, thereby loosening the clamp 200 from engagement with the flow sub lower housing 105b. The clamp 200 may then be opened and transported away from the flow sub 100. The spider 19 may then be operated to release the drill string 10. Once released, the top drive 5 may be operated to rotate 16 the drill string 10. Weight may be added to the drill bit 15, thereby advancing the drill string 10 into the wellbore 90 and resuming drilling of the wellbore. The process may be repeated until the wellbore 90 has been drilled to total depth or to a depth for setting another string of casing.

Alternatively, power tongs (not shown) may be used to add the modified stand 81 to the drill string instead of the rig crew returning to operate the tongs 65d,b and the spinner.

FIG. 6A illustrates an alternative drilling system 301 in the drilling mode, according to another embodiment of the present invention. The drilling system 301 may include the MODU 1m, the drilling rig 1r, a fluid handling system 301h, a fluid transport system 301t, and the PCA (not shown, see PCA 1p). The fluid transport system 301t may include the drill string 10, an upper marine riser package (UMRP) 320, the marine riser 25, the booster line 27, and the choke line 28. The UMRP 320 may include the diverter 21, the flex joint 22, the slip joint 23, and the tensioner 24. A lower end of the slip joint 23 may be connected to the upper end of the riser 25, such as by a flanged connection.

The fluid handling system **301h** may include a return line **329**, the mud pump **30d**, a bypass spool **331p**, the shale shaker **33**, the pressure sensors **35b,d**, a pressure gauge **335**, a rig choke **336**, a supply line, the shutoff valves **38a,b**, and a clamp **300**. A first end of the return line **329** may be connected to an outlet of the diverter **21** and a second end of the return line may be connected to the inlet of the shaker **33**. An upper end of the choke line **28** may be connected to the return line **329** or to the shaker inlet. The rig choke **336** and pressure gauge **335** may be assembled as part of the choke line **28**. A transfer line **361** may connect the outlet of the shaker **33** to the inlet of the mud pump **30d**. A lower end of the supply line may be connected to the outlet of the mud pump **30d** and an upper end of the supply line may be connected to the top drive inlet **5i**. The supply pressure sensor **35d** and supply shutoff valve **38a** may be assembled as part of the supply line. A first end of the bypass spool **331p** may be connected to the outlet of the mud pump **30d** and a second end of the bypass spool may be blind flanged in the drilling mode. The bypass pressure sensor **35b** and bypass shutoff valve **38b** may be assembled as part of the bypass spool **331p**. The umbilical **70** and the pressure sensors **35b,d** may be in communication with a rig controller (not shown).

In the drilling mode, the mud pump **30d** may pump the drilling fluid **60d** from the transfer line **361** (or fluid tank connected thereto), through the pump outlet, standpipe **337p** and Kelly hose **337h** to the top drive **5**. The drilling fluid **60d** may flow from the Kelly hose **337h** and into the drill string **10** via the top drive **5** and flow sub **100**. The drilling fluid **60d** may flow down through the drill string **10** and exit the drill bit **15**, where the fluid may circulate the cuttings away from the bit and return the cuttings up the annulus formed between an inner surface of the casing or wellbore and the outer surface of the drill string **10**. The returns may flow through the annulus to the wellhead. The returns may continue from the wellhead and into the riser **25** via the PCA. The returns may flow up the riser **25** to the diverter **21**. The returns may flow into the return line **329** via the diverter outlet. The returns may continue through to the shale shaker **33** and be processed thereby to remove the cuttings, thereby completing a cycle. As the drilling fluid and returns circulate, the drill string **10** may be rotated **16** by the top drive **5** and lowered by the traveling block **6**, thereby extending the wellbore into the lower formation.

If no instability has been detected, the drill string **10** may be extended in the drilling mode once a top of the drill string **10** reaches the rig floor **4** as discussed above for the drilling system **1**. If instability is detected, drilling may be halted by ceasing rotation of the drill string **10** and lowering of the top drive **5**. One or more of the BOPs may be engaged with the drill string **10** and one of the choke valves opened to divert the flow of returns into the choke line **28**. The rig choke **336** may or may not be tightened depending on the instability type. A density and/or other fluid property of the drilling fluid **60d** may be changed according to the instability type and drilling may resume once the altered drilling fluid has circulated. Once the drill string **10** needs to be extended, the drilling system **301** may be shifted into the bypass mode. Further, should the top drive **5** fail, the drilling system may be shifted into the bypass mode.

FIG. 6B illustrates the alternative drilling system **301** in the bypass mode. The clamp **300** may be similar to the clamp **200** except for omission of the actuator motors. The band and port valve actuator may be manually operated. Alternatively, the clamp **200** may be used in a manual override mode.

If shifting is due to the detection of instability, the drill string **10** may be extended in bypass mode once the top of the

drill string **10** reaches the rig floor **4**. In preparation of the shift, the stand may be replaced by the modified stand. Drilling may be stopped by stopping advancement and rotation **16** of the top drive **5** and removing weight from the drill bit **15**. The spider may then be operated to engage the drill string **10**. The manual clamp **300** may then be transported to the flow sub **100** and closed around the flow sub lower housing section **105b**. The blind flange may be removed from the bypass spool **331p** and a hose **331h** connected to the bypass spool and the clamp **300**. The rig crew may then manually rotate the tensioner bolt, thereby tightening the clamp **300** into engagement with the flow sub lower housing **105b**. The backup tong **65b** may be engaged with the top of the drill string **10**. The rig crew may then open the bypass valve **38b**. The rig crew may then manually rotate the lead screw, thereby raising the yoke and moving the flow sub sleeve. The upward movement of the sleeve may close the flow sub bore valve. Drilling fluid **60d** may momentarily flow into the drill string **10** through both the side port **101** and the bore valve. Once the side port **101** is fully open, the rig crew may close the supply valve **38a** and the modified stand may be added to the drill string **10** as discussed above.

If shifting is due to failure of the top drive **5**, the rig crew may then hoist the clamp **300** to the flow sub **100** at the height where the top drive stalled. The blind flange may be removed from the bypass spool **331p** and a hose **331h** connected to the bypass spool and the clamp **300**. The rig crew may then manually rotate the tensioner bolt, open the bypass valve **38b**, and manually rotate the lead screw. Once the side port **101** is fully open, the rig crew may close the supply valve **38a** and manually disconnect the quill **5q** from the flow sub **100**. The top drive **5** may then be raised clear of the flow sub **100** and serviced or replaced. Circulation may be maintained during the servicing of the top drive **5**. Once the top drive **5** is again operational, the quill **5q** may be reconnected to the flow sub **100** and flow restored through the top drive. Drilling may then continue in the drilling mode (no need to add the second flow sub). The bypass mode of the drilling system **1** may also be employed for top drive servicing in a similar fashion.

FIG. 7 illustrates optional accessories for a top drive system of any of the drilling systems **1, 301, 501**. The top drive system may include the top drive **5** and the flow sub **100**. The top drive system may further include one or more of: a saver sub **400s**, an internal blowout preventer (IBOP) **400k**, a torque sub **400t**, and an MSV **400m**. The saver sub **400s** may be directly connected to the quill **5q**. The saver sub **400s** may be tubular, have a bore formed therethrough, and have couplings, such as a threaded box or pin, formed at each end thereof. The saver sub **400s** may endure wear caused by repeated connection and disconnection of other components to the top drive **5** instead of the quill **5q** having to endure the wear. Alternatively, the saver sub **400s** may be an adapter having a different size and/or type of lower coupling.

The IBOP **400k** may include a housing **401**, a closure member, such as a ball **402**, a seat **403**, and a linkage **404**. The housing **401** may be tubular, have a bore formed therethrough, and have couplings, such as a threaded box or pin, formed at each end thereof. The housing **401** may include one or more sections (not shown), such as an upper section and a lower section, each section connected together, such as by a threaded connection. A chamber may be formed between the housing sections for receiving the ball **402** and seat **403**. The ball **402** may be rotatable relative to the seat **403** between an open position (shown) and a closed position (not shown) by the linkage **404**. The linkage **404** may interact with an actuator (not shown) of the top drive **5** for opening and closing the ball **402**. In the closed position, engagement of the ball **402**

with the seat 403 may seal the bore against upward flow of fluid from the drill pipe 10 to serve as a barrier in a well control event.

The torque sub 400_t may include an outer non-rotating interface 418, an interface frame 416_f, an inner torque shaft 410, one or more load cells 414_{a,t}, one or more wireless couplings, a shaft electronics package 415_r, an interface electronics package 415_s, a turns counter, and a shield 416_s. The shaft 410 may be tubular, have a bore formed therethrough, and have couplings, such as a threaded box or pin, formed at each end thereof. The shaft 410 may have a reduced diameter outer portion forming a recess in an outer surface thereof. The load cell 414_t may include a circuit of one or more torsional strain gages and the load cell 414_a may include a circuit of one or more longitudinal strain gages, each strain gage attached to an outer surface of the reduced diameter portion, such as by adhesive. The strain gages may each be made from metallic foil, semiconductor, or optical fiber.

The wireless couplings may include wireless power couplings and wireless data couplings. Each set of couplings may include a shaft member connected to the shaft and an interface member housed in an encapsulation 417_s connected to the frame 416_f. The wireless power couplings may each be inductive coils 411_{r,s} and the wireless data couplings may each be antennas 412_{r,s}. The shaft electronics may be connected by leads and the electronics package 415_r, load cells 414_{a,t}, and antenna 412_r may be encapsulated 417_r into the recess. The shield 416_s may be located adjacent to the recess and may be connected to the frame 416_f. Alternatively, the shield 416_s may be connected to the shaft 410. The frame 416_f may be connected to the top drive frame 5_f by a bracket (not shown). Alternatively, the frame 416_f may be connected to the torque shaft 410 by a swivel and have a bracket for torsional arrest by the rail 18.

The shaft electronics package 415_r may include a microcontroller, a power converter, an ammeter and a transmitter. The power converter may receive an AC power signal from the power coupling and convert the signal to a DC power signal for operation of the shaft electronics. The DC power signal may be supplied to the load cells 414_{a,t} and the ammeter may measure the current. The microcontroller may receive the measurements from the ammeter and digitally encode the measurements. The transmitter may receive the digitally encoded measurements, modulate them onto a carrier signal, and supply the modulated signal to the antenna 412_r.

The interface antenna 412_s may receive the modulated signal and the interface electronics package 415_s may include a receiver for demodulating the signal. The interface package 415_s may further include a microcontroller for digitally decoding the measurements and converting the measurements to torque and longitudinal load. The interface package 415_s may send the converted measurements to the PLC 75 or rig controller via a data cable. The interface package 415_s may further include a power converter for supplying the interface data coupling with the AC power signal. The interface package 415_s may also be powered by the data cable or include a battery.

The turns counter may include a base 413_h torsionally connected to the shaft, a turns gear 413_g connected to the base, and a proximity sensor 413_s connected to the frame 416_f and located adjacent to the turns gear. The base 413_h may be made from a nonmagnetic material, the 413_g gear may be made from a magnetic material or permanently magnetic material, and the proximity sensor 413_s may be a Hall Effect sensor. The proximity sensor 413_s may include a semiconductor head and the interface package 415_s may supply the head with a regulated current. The interface electronics pack-

age 415_s may further include a voltmeter for detecting Hall voltage generated by rotation of the turns gear 413_g relative to the proximity sensor 413_s. The interface controller may then convert the measurement to angular speed and supply the converted measurement to the PLC 75 or rig controller.

During the drilling operation, the PLC 75 or rig controller may monitor torque, longitudinal load, and angular velocity for instability, such as sticking of the drill pipe 10 or collapse of the lower formation 104_b.

10 The MSV 400_m may include a housing 420, a piston 421, a seat 423, a plug 426, and a spring 427. The housing 420 may be tubular, have a bore formed therethrough, and have couplings, such as a threaded box or pin, formed at each end thereof. The housing 420 may also have an enlarged portion 15 forming a recess in an inner surface thereof and a reduced portion connected by a shoulder. The piston 421 may have a head portion and a sleeve portion connected by a shoulder. The piston 421 may be disposed in the housing 420 and longitudinally movable relative thereto between a closed 20 position (shown) and an open position (not shown). A chamber may be formed between the piston shoulder and the housing shoulder. The spring 427 may be disposed in the chamber against the shoulders and may bias the piston 421 toward the closed position. The spring 427 may be low profile, such as a 25 Belleville spring.

The seat 423 may include an outer ring, an inner ring, and spokes connecting the rings. The spokes may be spaced apart to form flow passages therebetween. The seat 423 may be connected to the housing 420, such as by entrapment of the 30 outer ring between a lip formed in the inner surface of the housing and a retainer, such as a snap ring received by a groove formed in the housing inner surface. The seat 423 may be made from the erosion resistant material. A cap 422 may be connected to the piston head, such as by an interference fit. 35 The cap 422 may be made from the erosion resistant material. In the closed position engagement of the cap 422 with the seat 423 may seal the bore, thereby preventing spillage of drilling fluid 60_d while adding the stand 11_a in the drilling mode.

The plug 426 may be fastened to the seat 423, such as by 40 one or more shearable fasteners. The plug 426 may have bypass flow passages formed therethrough. A shim 424 may be fastened to the plug by entrapment between a top of the plug 426 and a tab of a fishing neck 425. The shim 424 may flex between an open position (not shown) and a closed position 45 (shown) and may close the passages in the closed position. The fishing neck 425 may be connected to the plug 426, such as by a threaded connection.

In operation, the piston 421 may move to the open position 50 by fluid pressure exerted by the mud pump 30_d during drilling. Once injection has stopped for adding the stand 11_a, the spring 427 may move the piston 421 to the closed position. The spring 427 may exert sufficient force on the piston 421 to counter weight of the drilling fluid 60_d in the top drive system and Kelly hose. Should pressure in the drill string 10 ever 55 exceed pressure in the top drive system, the shim 424 may open to equalize pressure so as not to blind the supply pressure sensor 38_a.

Should the MSV 400_m be released with the flow sub 100 in bypass mode and it becomes necessary to deploy wireline through the drill string 10, the fishing neck 425 may be engaged by a fishing tool (not shown). Sufficient upward force exerted on the fishing neck 425 may break the shearable fasteners, thereby releasing the fishing neck and plug 426.

FIGS. 8A-8C illustrate an alternative drilling system 501 in 60 a reverse bypass mode, according to another embodiment of the present invention. The drilling system 501 may include the MODU 1_m, the drilling rig 1_r, a fluid handling system

501h, a fluid transport system **501t**, and the PCA **1p**. The fluid transport system **501t** may include a drill string **510**, the upper marine riser package (UMRP) **320**, the marine riser **25**, the booster line **27**, and a choke line **528**. The drill string **510** may be similar to the drill string **10** except for the BHA **510b** further including a circulation sub **512** and a control module (only stinger thereof shown).

The circulation sub **512** may include a body, an adapter, a piston, a mandrel, a biasing member, such as spring, and one or more fasteners, such as anti-rotation screws. The body may be tubular and have a longitudinal bore formed therethrough. Each longitudinal end of the body may be threaded for longitudinal and rotational connection to other members, such as a control module (not shown) at an upper end thereof and the adapter at a lower end thereof. The body may have one or more flow ports formed through a wall thereof. The body may also have a chamber formed therein at least partially defined by shoulder for receiving the piston. An end of the adapter distal from the body may also be threaded for longitudinal and rotational connection to another member of the BHA **510b**. The mandrel may be a tubular, have a longitudinal bore formed therethrough, and may be disposed in the body bore. The mandrel may have a flow port formed through a wall thereof corresponding to each body port. The piston may be annular, have a longitudinal bore formed therethrough, and be longitudinally connected to a lower end of the mandrel, such as by a threaded connection.

In operation, the control module may receive a wireless instruction signal from the MODU **1m**. The instruction signal may direct the control module to allow movement of the circulation sub **512** to an intermediate position. The module controller may open a solenoid valve of the control module. As drilling fluid is being circulated through the BHA **510b**, the circulation sub piston may then move the mandrel and a follower of the control module to the intermediate position. During movement to the intermediate position, the mandrel ports may move out of alignment with the body ports and the stinger may move clear of the body ports. During movement, the module controller may monitor the circulation sub **512** using a position sensor. Once the mandrel has reached the intermediate position, the module controller may close the solenoid valve.

Flow of drilling fluid may then be halted. Pressure between the bore of the circulation sub **512** and the annulus **95** may equalize and the circulation sub spring may push the circulation sub piston and the mandrel to the open position. The module follower may be restrained from following the mandrel by the closed solenoid valve and the mandrel port may re-align with the body port, thereby opening the ports and providing fluid communication between a bore of the drill string and the annulus **95**.

The fluid handling system **501h** may include a return line **529**, the mud pump **30d**, a bypass line, the shale shaker **33**, the pressure sensors **35b,d**, the pressure gauge **335**, the rig choke **336**, the supply line, a reverse supply line **537**, shutoff valves **38a,b** **538a-c**, and the clamp **300**. A first end of the return line **529** may be connected to an outlet of the diverter **21** and a second end of the return line may be connected to the inlet of the shaker **33**. The shutoff valve **538b** may be assembled as part of the return line **529**. An upper end of the choke line **528** may be connected to the shaker inlet. The rig choke **336**, pressure gauge **335**, shutoff valve **538c**, and a lower reverse supply spool **537p** may be assembled as part of the choke line **528**. The lower reverse supply spool **537p** may be blind flanged in the drilling mode. The upper reverse supply spool **331p** may be connected to the outlet of the mud pump **30d** and may be blind flanged in the drilling mode. A first end of the

bypass spool **531p** may be connected to the shaker inlet and a second end of the bypass spool may be blind flanged in the drilling mode.

In the drilling mode, the mud pump **30d** may pump the drilling fluid **60d** from the transfer line **361** (or fluid tank connected thereto), through the pump outlet, standpipe **337p** and Kelly hose **337h** to the top drive **5**. The drilling fluid **60d** may flow from the Kelly hose **337h** and into the drill string **510** via the top drive **5** and flow sub **100**. The drilling fluid **60d** may flow down through the drill string **510** and exit the drill bit **15** (circulation **512** sub closed), where the fluid may circulate the cuttings away from the bit **15** and return the cuttings up the annulus **95**. The returns **60r** may flow through the annulus **95** to the wellhead **50**. The returns **60r** may continue from the wellhead **50** and into the riser **25** via the PCA **1p**. The returns **60r** may flow up the riser **25** to the diverter **21**. The returns **60r** may flow into the return line **529** via the diverter outlet. The returns **60r** may continue through the open shutoff valve **538b** to the shale shaker **33** and be processed thereby to remove the cuttings, thereby completing a cycle. As the drilling fluid **60d** and returns **60r** circulate, the drill string **10** may be rotated **16** by the top drive **5** and lowered by the traveling block **6**, thereby extending the wellbore **90** into the lower formation **94b**.

If no instability has been detected, the drill string **10** may be extended in the drilling mode once a top of the drill string **10** reaches the rig floor **4** as discussed above for the drilling system **1**. If instability is detected and/or should the top drive **5** fail, the drilling system **501** may be shifted into the (forward) bypass mode as discussed above for the drilling system **301**.

Periodically, a cleaning operation may be performed to remove residual cuttings from the wellbore **90** that forward circulation of the drilling fluid **60d** is unable to transport to the MODU **1m**. The drilling system **501** may be shifted into the reverse bypass mode for the cleaning operation. Drilling may be stopped by stopping advancement and rotation **16** of the top drive **5**. The instruction signal may be sent to the control module to open the circulation sub **512**. The manual clamp **300** may then be transported to the flow sub **100** and closed around the flow sub lower housing section **105b**. The blind flange may be removed from the bypass spool **531p** and a hose **531h** connected to the bypass spool and the clamp **300**. The blind flanges may be removed from the upper and lower reverse supply spools **331p**, **537p** and a hose **537h** may be connected to the reverse supply spools.

The rig crew may then manually rotate the tensioner bolt, thereby tightening the clamp **300** into engagement with the flow sub lower housing **105b**. The PCA valve **45e** and the reverse supply valve **38b** may then be opened and the supply valve **38a** closed, thereby diverting the drilling fluid supply down the choke line **528** and into the PCA bore. The rig crew may then manually rotate the lead screw, thereby raising the yoke and moving the flow sub sleeve. The upward movement of the sleeve may close the flow sub bore valve. Once the side port **101** is fully open, the rig crew may open the bypass valve **538a** and close the return valve **538b**. The annular BOP **42a** and the upper one **42u** of the ram preventers **42u,b** may then be closed against the drill string **10**, thereby forcing the drilling fluid **60d** down the annulus **95**. The drilling fluid **60d** may wash the residual cuttings from the annulus **95**. The returns **60r** may be discharged from the annulus **95** into the open circulation sub **512**. The returns **60r** may continue up the drill string **510** at an increased velocity relative to forward circulation, thereby improving cuttings carrying capability. Once the annulus **95** has been cleaned, the system **501** maybe

shifted back to the drilling mode for continuation of the drilling operation (unless total depth has been reached, then to a tripping mode).

Alternatively, the reverse bypass mode may be utilized if instability is detected. In such a situation, the reverse bypass mode may be used to circulate out a kick of formation fluid and/or to bullhead the lower formation 94b. The circulation sub 512 may be opened for circulating a kick and remain closed for bullheading. Additionally, the control module may repeatedly open and close the circulation sub 512 so that the cleaning and/or kick circulation operations may be performed periodically after drilling a segment of the lower formation and/or while tripping the drill string into and/or from the wellbore.

Alternatively, the drilling system 1 may be modified to have reverse bypass mode capability by connecting a reverse supply line from the bypass spool 37p to the RCD outlet (would now be an inlet) and connecting the bypass hose 37h to the shaker inlet. The drilling fluid 60d would then be injected into the RCD inlet and be forced by the RCD 26 to flow down the riser 25 into the annulus 95 instead of being injected down the choke line with the BOPs closed.

FIGS. 9A-9C illustrate an alternative drilling system 601 in a reverse drilling mode, according to another embodiment of the present invention. The drilling system 601 may include the MODU 1m, the drilling rig 1r, a fluid handling system 601h, a fluid transport system 601t, the PCA 1p, and the PLC. The fluid transport system 601t may include a drill string 610, the upper marine riser package (UMRP) 20, the marine riser 25, the booster line, and the choke line. The drill string 610 may be similar to the drill string 10 except for the BHA 610b further including a drilling motor, such as progressive cavity motor 612 and a reverse circulation drill bit 615 instead of the (forward circulation) drill bit 15.

The motor 612 may include a dump valve (not shown), a power section, a mechanical joint, and a bearing section (not shown). The power section may harness fluid energy from the returns 60r and utilize the harnessed energy to rotationally drive the drill bit 615. The power section may include a rotor, a stator, and a stator housing. The rotor and stator housing may be made from a metal or alloy or a corrosion resistant alloy. The stator may be made from an elastomer or an elastomeric copolymer.

The rotor may have one or more lobes formed in an outer surface thereof and helically extending therealong. For interaction with the rotor lobes, the stator may have two or more lobes (equal to the number of rotor lobes plus one) formed in an outer surface thereof and helically extending therealong. The rotor and stator may interact at the helical lobes to form a plurality of cavities (aka chambers) and sealing surfaces isolating the cavities from the each other. To effectuate the seal, the rotor and stator may be sized to form an interference fit. Alternatively, the stator housing may have the lobed profile formed in an inner surface thereof, thereby allowing a thickness of the stator to be reduced and to be uniform.

The fluid handling system 601h may include a return line 629, the mud pump, the shale shaker, the supply and returns flow meters, the supply and returns pressure sensors, the returns choke, a supply line 637, and the clamp 300. An upper end of the return line 629 may be connected to the clamp inlet (now an outlet) and a lower end of the return line may be connected to the shaker inlet. The returns choke, returns pressure sensor, and returns flow meter may be assembled as part of the return line 629. An upper end of the supply line 637 may be connected to the mud pump outlet and a lower end of the supply line may be connected to the RCD outlet (now an

inlet). The supply pressure sensor, and supply flow meter may be assembled as part of the supply line 637.

In the reverse drilling mode, the mud pump 30d may pump the drilling fluid 60d from the transfer line 361 (or fluid tank 5 connected thereto), through the pump outlet and supply line 637 to the RCD. The drilling fluid 60d may flow down the riser 25 and the drill string 610, through the PCA 1p, and into the annulus, where the fluid may circulate the cuttings into the bit 615. The returns 60r may flow through the BHA 610b, 10 thereby powering the motor 612 to rotate 16 the bit 615. The returns 60r may continue from the BHA 610b, through the drill pipe 10p, and to the CFS 100 (in the side injection mode). The returns 60r be diverted by the CFS 100 into the return line 629 via the clamp outlet. The returns 60r may continue 15 through the returns pressure sensor, returns choke, and returns flow meter to the shale shaker 33 and be processed thereby to remove the cuttings, thereby completing a cycle. As the drilling fluid 60d and returns 60r circulate, the drill bit 10 may be rotated 16 by the motor 612 and lowered by the 20 traveling block 6, thereby extending the wellbore 90 into the lower formation 94b.

If no instability has been detected, the drill string 610 may be extended in the reverse drilling mode once a top of the drill string reaches the rig floor by adding the stand 11a. Extension 25 of the drill string in reverse drilling mode may be similar to extension of the drill string 10 of drilling system 1 in drilling mode except that the CFS 100 may remain in the side injection mode with the clamp 300 engaged with the CFS and a rotary table (not shown) of the drilling rig may be used instead 30 of the drive tong to make up the connection between the CFS 100 and the added stand by rotating the drill string 610 instead of the CFS. If instability is detected, the drilling system 601 may be extended while maintaining continuous circulation by: disconnecting the top drive from the CFS 100, connecting 35 the modified stand to the drill string 610, connecting the top drive to the modified stand, engaging a second clamp (not shown) to the second CFS of the modified stand (at a height from the rig floor), connecting a return bypass line to the second CFS (at the height), switching the second CFS to side 40 injection mode, and switching the CFS 100 to the top injection mode.

Alternatively, the drilling system 601 may be convertible between the reverse circulation drilling mode and a forward circulation drilling mode.

Alternatively, the drilling system 601 may include a rotating CFS (not shown) or rotating clamp (not shown) instead of the CFS 100 or clamp 300, as discussed in US Pat. Pub. No. 2011/0155379, which is herein incorporated by reference in its entirety. The rotating CFS or clamp may allow use of the top drive to make up the connections and/or to drill the wellbore while the clamp is engaged with the CFS.

Alternatively, any of the drilling systems 1, 301, 501, 601 may be utilized for running casing or liner to reinforce and/or drill the wellbore 90, or for assembling work strings to place 55 downhole components in the wellbore.

While the foregoing is directed to embodiments of the present invention, other and further embodiments of the invention may be devised without departing from the basic scope thereof, and the scope thereof is determined by the 60 claims that follow.

The invention claimed is:

1. A method for deploying a tubular string into a wellbore, comprising:
65 injecting fluid through a top drive and a flow sub into a top of the tubular string and lowering the tubular string into the wellbore, wherein:

25

the flow sub connects the tubular string top to a quill of the top drive,
 the flow sub is in a top injection mode, and
 the flow sub has:
   a closed port formed through a wall thereof, and
   an open bore conducting the fluid from the quill into the tubular string top;
 halting injection of the fluid through the top drive and the tubular string and halting lowering of the tubular string; while injection and lowering are halted:
   disconnecting the flow sub from the tubular string top;
   adding one or more tubular joints to the tubular string; and
   connecting the flow sub to a top of the added joints; and
   resuming injection of the fluid through the top drive and lowering of the tubular string. 15

2. The method of claim 1, further comprising:
 halting lowering of the tubular string;
 while lowering is halted, shifting the flow sub to a side injection mode, thereby opening the port and closing the bore, and injecting the fluid into the port; and
 while injecting the fluid into the port:
   halting injection of the fluid through the top drive;
   disconnecting the quill from the flow sub; and
   adding a stand to the tubular string, the stand having a second flow sub and one or more of the tubular joints. 25

3. The method of claim 2, further comprising monitoring an exposed formation adjacent to the wellbore for instability, wherein the flow sub is shifted to the side injection mode in response to detection of the instability. 30

4. The method of claim 3, wherein the formation is monitored by:
 measuring a flow rate of the injected fluid;
 measuring a flow rate of fluid returning from the wellbore; 35 and
 comparing the flow rates.

5. The method of claim 2, wherein each flow sub comprises:
 a port valve for closing the port in the top injection mode and for opening the port in the side injection mode, and a bore valve operably coupled to the port valve for opening the bore in the top injection mode and for closing the bore in the side injection mode. 40

6. The method of claim 5, wherein:
 the flow sub is shifted to the side injection mode by:
   engaging the flow sub with a clamp; and
   operating an automated actuator of the clamp to open the port valve, thereby also closing the bore valve, and the fluid is injected into the port via an inlet of the clamp. 50

7. The method of claim 1, wherein:
 the tubular string is a drill string having a drill bit disposed at a bottom thereof, the fluid is mud, and the method further comprises rotating the drill bit while injecting the mud and lowering the drill string, thereby drilling the wellbore. 55

8. The method of claim 1, further comprising:
 halting lowering of the tubular string due to failure of the top drive; and
 while lowering is halted:
   shifting the flow sub to a side injection mode, thereby opening the port and closing the bore, and injecting the fluid into the port; and
   while injecting the fluid into the port:
     disconnecting the quill from the flow sub; and
     servicing or replacing the top drive. 60

26

9. A top drive system, comprising:
 a flow sub, comprising:
   a tubular housing having: a longitudinal bore formed therethrough, a flow port formed through a wall thereof, an upper coupling, and a lower coupling for connection to a tubular;
   a bore valve operable between an open position and a closed position, wherein the bore valve allows free passage through the bore in the open position and isolates an upper portion of the bore from a lower portion of the bore in the closed position; and
   a valve member for selectively opening and closing the flow port; and
 a top drive comprising:
   a motor operable to rotate a quill;
   a swivel having an inlet for receiving a kelly hose and an outlet in fluid communication with the quill; and
   a backup wrench movable between an upper position and a lower position, wherein:
     the motor, swivel, and backup wrench are connected together to form a frame of the top drive,
     the upper coupling is connected to the quill,
     the backup wrench is engageable with an upper portion of the tubular housing in the upper position, the backup wrench is engageable with a threaded coupling of the tubular housing in the lower position,
     the valve member is a sleeve,
     the sleeve is disposed in the tubular housing,
     the sleeve is movable between an open position where the flow port is exposed to the bore and a closed position where a wall of the sleeve is disposed between the flow port and the bore, and
     the flow sub further comprises a bore valve actuator operably coupling the sleeve and the bore valve such that opening the sleeve closes the bore valve and closing the sleeve opens the bore valve. 55

10. The system of claim 9, further comprising a clamp comprising:
 an inlet for injecting fluid into the flow port and operable to engage the valve member and seal against a surface of the tubular housing adjacent to the flow port; and
 an automated valve actuator for operating the valve member to open and close the port. 60

11. The system of claim 9, further comprising an internal blowout preventer comprising a valve member, a seat, and a linkage operable by the top drive to open and close the valve member, wherein the internal blowout preventer connects the flow sub to the quill. 65

12. The system of claim 9, further comprising a torque sub comprising a turns counter and a torque shaft having a load cell and connecting the flow sub to the quill. 70

13. The system of claim 9, further comprising a mud saver valve operable to open in response to fluid pumped through the top drive and to close in response to cessation of pumping. 75

14. A method for deploying a tubular string into a wellbore, comprising:
 injecting fluid through a top drive and a flow sub into a top of the tubular string and lowering the tubular string into the wellbore, wherein:
   the flow sub connects the tubular string top to a quill of the top drive;
   the flow sub is in a top injection mode, and
   the flow sub has:
     a port formed through a wall thereof,
     a valve member closing the port, and
     an open bore conducting the fluid from the quill into the tubular string top; 80

halting lowering of the tubular string; and while lowering is halted, shifting the flow sub to a side injection mode, thereby moving the valve member to open the port and closing the bore, and injecting the fluid into an annulus of the wellbore, thereby circulating from the annulus, up a bore of the tubular string, and to the port. 5

15. A method for deploying a tubular string into a wellbore, comprising:

injecting fluid into an annulus of the wellbore, thereby 10 circulating from the annulus, up a bore of the tubular string, and to an open port of a flow sub connected to a top of the tubular string and lowering the tubular string into the wellbore,

wherein:

the tubular string has a bottomhole assembly, 15

the bottomhole assembly includes a reverse circulation

drill bit and a drilling motor, and

the drilling motor utilizes the injected fluid to rotate the 20 drill bit, thereby drilling the wellbore;

halting injection of the fluid through the annulus and the 20 tubular string and halting lowering of the tubular string;

while lowering is halted:

disconnecting the flow sub from the tubular string top;

adding one or more tubular joints to the tubular string

and connecting the flow sub to a top of the added 25

joints; and

resuming lowering of the tubular string.
